United States Patent Office

Des. 214,421
Patented June 17, 1969

214,421

JUG

John Brady Campbell, Paramus, and Willard R. Horne,
Northvale, N.J., assignors to The Procter & Gamble
Company, Cincinnati, Ohio, a corporation of Ohio

Filed June 27, 1968, Ser. No. 12,519

Term of patent 14 years

Int. Cl. D9—01

U.S. Cl. D9—42

FIG. 6

FIG. 7

FIG. 8

FIG. 9

FIG. 1 is a front elevational view of a jug showing our new design;

FIG. 2 is a side elevational view thereof as seen from the right of FIG. 1;

FIG. 3 is a side elevational view thereof as seen from the left of FIG. 1;

FIG. 4 is a top plan view thereof;

FIGS. 5, 6, 7 and 8 are cross sectional views thereof taken, respectively, on the line 5—5, 6—6, 7—7 and 8—8 of FIG. 1 looking downward; and

FIG. 9 is a bottom plan view thereof.

The side not shown is a mirror image of the side shown.

We claim:

The ornamental design for a jug, as shown and described.
